TRAFFIC SIGNAL

Godfrey Gort and Walter Dinnerville, Chicago,
Ill., assignors to Western Railroad Supply
Company, Chicago, Ill., a corporation of Del-
aware

Application November 11, 1935, Serial No. 49,138

4 Claims. (Cl. 177—329)

This invention relates to traffic signals, particularly adapted for railway crossings.

One of the objects of the invention is to give a signal in a positive manner when a car or train is approaching a place to be guarded, and to retire the signal from view when there is no danger.

Another object is to provide means for automatically moving the stop signal to its signaling or danger-indicating position when a train is approaching the place to be guarded and also when the electric current or the mechanism fails for any reason, and to provide motor driven means for moving the signal to non-danger or 15 "clear" position, that is, with its face longitudinally of the highway.

Another object of the invention is to so mount and protect the stop sign that its operation cannot be interfered with by ice or snow.

Another object is to provide means for preventing unauthorized manipulation of the signal.

Another object is to provide simplified, compact and relatively inexpensive mechanism efficient for its intended purposes.

In that embodiment of the invention shown in the drawings—

Fig. 1 is a front elevation of a traffic signal embodying our invention.

Fig. 2 is a side elevation of the same.

Fig. 3 is a front view of the control mechanism with most of the housing broken away.

Fig. 4 is a side view, looking at the mechanism shown in Fig. 3 from the right side.

Fig. 5 is a horizontal sectional view taken on the line 5—5 of Fig. 3, showing the motor control switch in closed position.

Fig. 6 is a view similar to Fig. 5, showing the switch in open position.

Fig. 7 is a horizontal sectional view taken on the line 7—7 of Fig. 3, looking downwardly as indicated by the arrows.

Fig. 8 is a horizontal sectional view of the same parts shown in Fig. 7 but in different positions.

Fig. 9 is a diagrammatic view of the electrical circuits used in connection with the control mechanism.

Fig. 10 is a horizontal sectional view of the control mechanism taken on the line 10—10 of Fig. 4.

Fig. 11 is a vertical sectional view taken on the line 11—11 of Fig. 10.

In Figs. 1 and 2, the standard 10 supports the control mechanism housing 11, shield 12, sig-

nal member 13, lights 14, and track and crossing signs 15 and 16, respectively.

The mechanism for controlling the signal 13 is located within the housing 11 and is shown in its preferred form in Figs. 3 to 11, inclusive. In said preferred embodiment, the motor 17 drives the shaft 18 and worm 19. The worm 19 meshes with the worm wheel 20 (Figs. 7 and 11) which is keyed to the bushing 21 non-fixedly mounted on the vertical shaft 22 which is rotatably journaled in the frame 23. Said bushing 21 carries a spur gear 24 which meshes with two small pinion gears 25, 25, located in and carried by a collar 26. Supported by the casting 26 is a ratchet wheel 27 which is rotatable relatively to the shaft 22. A ring gear 28 is fixed within the ratchet wheel 27 by screws 29, in mesh with pinion gears 25, 25. The pinion gears 25, 25 rotate on shafts 30, 30 which are fixed in the collar 26 by keys (not shown) and said collar is keyed at 31 to the vertical shaft 22.

The shaft 22 has fixed to it a disc 32 cut away at 33. The disc 32 is provided with a projecting base portion 34 which carries a vertically disposed pin 35. The pin 35 is designed to engage a slot 36 in a disc 37 fastened on the signal shaft 38. The disc 37 is cut away at two places, 39, 40, the centers of the cut away portions being 90° apart. The signal shaft 38 is mounted in the frame 41 which is part of the frame 23, and at the lower end said shaft 38 carries the signal 13 below the housing 11.

The shaft 22 has keyed to it a bevel gear 42, which meshes with a slightly larger bevel gear 43 keyed to a horizontal shaft 44, supported in the frame 23. The shaft 44 has bolted to it, by a bolt 45, a weight 46.

From the foregoing it will be understood that the motor raises the weight 46 by the following means: shaft 18, worm 19, worm wheel 20, bushing 21, spur gear 24, pinion gears 25, collar 26, key 31, shaft 22, beveled gears 42, 43, and shaft 44. Simultaneously, the signal 13 is turned to clear position by shaft 22, disc 32, pin 35, disc 37 and shaft 38.

When the weight 46 drops as hereinafter explained, the signal 13 is automatically turned to danger-indicating position through actuation of shaft 44, bevel gears 43, 42, shaft 22, disc 32, pin 35, disc 37, and signal shaft 38.

The base 47 of the frame 23 supports a casting 48 on which is pivotally mounted a pawl 49 by pivot pin 50. The pawl has a tooth 51 which may engage the ratchet wheel 27. The pawl has connected to it an arm 52, pivotally mounted at 55

53 on supports 54 connected with the casting 48. The arm 52 carries an armature 55 adapted to be attracted by the cores of multiple coils 56 in a circuit to be described. The coils are fixed 5 to the casting 48 by screws 57.

A motor-controlling switch 58 in the said circuit is supported by a bracket 59 fastened to the frame 23 by screws 60. The switch comprises a pair of contact arms 61 and 62. The arm 61 has fastened to it an insulated block 63 which is adapted to be contacted by an insulated cam 64 fastened to the hub of the disc 32 on the shaft 22. Fig. 5 shows the switch arms 61 and 62 in closed position and Fig. 6 shows the cam 64 engaging the insulated contact member 63, flexing the arm 61 and opening the switch.

In Fig. 9 is shown the circuit arrangement which may be used in connection with the subject matter of this invention. Connected across 20 a section of rails (not shown) having a local source of power, is a relay 65. We have shown two relays 65, one for each of two track circuits. The relay armatures 66 and contacts 67 are in circuit with the conductors 68, 69, of a circuit 25 having a suitable source of supply such as the battery 70. Also in circuit with the conductors 68, 69 are the motor 17 and the parallel windings 71, 72 of the compound coils 56. The motor circuit and the low resistance winding 72 are connected in parallel and include said switch members 61, 62.

When there is no train within the section of track to be guarded, and the electrical circuits are functioning normally, the relays 65 are energized and the positions of the several parts of the control mechanism are as follows: the pawl 49 is in engagement with ratchet wheel 27, the weight 46 is in raised or horizontal position as shown in Fig. 8, and the signal is in clear or non-signalling position. The weight is prevented from dropping by the fact that the pawl 49 engages the ratchet 27 and thereby prevents rotation of the shaft 22. The relays 65 hold the armatures 66 and contacts 67 in contact, and the circuit being thus closed, the pawl operating armature 55 is attracted to the cores of the magnetic coils 56 by the high resistance winding 71 which is in circuit and holds the pawl 49 in engagement with the ratchet wheel 27, notwithstanding 40 the fact that at this time the switch 61—62 in the motor circuit and winding 72 is open, as shown in Fig. 9, due to the action of the cam 64 on switch arm 61.

When a train reaches the section of track to be guarded, the magnetic relay 65 is short circuited and de-energized, thereby allowing armature 66 to break contact with contact 67, opening line 68—69, and de-energizing the windings 71, 72 of coils 56. Consequently the armature 55 drops away from the cores of the coils 56, disengaging the pawl 49 from ratchet 27.

The dropping of the armature 55 and disengagement of the pawl 49 from the ratchet 27 allows the weight 46 to drop by gravity to vertical 65 position, thus rotating shaft 22 counterclockwise by means of shaft 44, and bevel gears 43, 42. Such actuation of the shaft 22 carries with it the collar 26, pinion gears 25, ring gear 28 and ratchet 27. The spur gear 24, bushing 21 and worm wheel 20 are not affected. The rotation of shaft 22 by the dropping of the weight 46 rotates the disc 32 counterclockwise for a little more than a quarter turn, causing the pin 35 70 to engage the slot 36 in the disc 37 on the signal shaft 38, automatically bringing the disc 37

to the position shown in Fig. 7 and turning the signal shaft 38 one quarter turn and the signal 13 to danger-indicating position as shown in Fig. 1. At this time, the shaft 22 has moved to such position that the cam 64 is not engaging the switch arm 61, as shown in Fig. 5, and the motor circuit switch 61—62 is closed, but the line 68—69 is still open, due to the presence of the train and the resultant open position of armature 66 and contact 67.

When the train has departed, the relay 65 is re-energized, armature 66 is put into contact with contact 67, and the motor circuit is completed. The armature 55 is drawn into contact with the magnetized coils 56, causing pawl 49 to re-engage ratchet 27. As soon as the circuit has been closed, the motor 17 drives shaft 18, worm 19, worm wheel 20, bushing 21 and spur gear 24, thus actuating pinion gears 25. Since the ring gear 28 and ratchet 27 are a unit, and the ratchet is being held against rotation, the pinion gears 25 travel around the ring gear 28, imparting rotation to the collar 26 and the shaft 22 keyed to said casting by pin 31. Shaft 22 rotates the bevel gears 42, 43 and shaft 44, lifting the weight 46 to horizontal position, and at the same time the disc 32 is rotated clockwise to the position shown in Fig. 8, the pin 35 engaging disc 37 and actuating the signal shaft 38 to turn the signal 13 to clear or non-danger position.

The rotation of the shaft 22 to lift the weight 46 brings the cam 64 into engagement with the switch arm 61, as shown in Fig. 6, opening motor switch and stopping the motor as soon as the weight has been raised. But the circuit including winding 71 remains closed and, therefore, the armature 55 is held in contact with coils 56, the pawl is in ratchet-engaging position as shown in Fig. 8, and the weight is prevented from dropping until the electric current fails or the relay 65 is de-energized by the short circuiting produced by a train entering the section of track to be guarded, as heretofore explained.

At the end of the clockwise movement of the shaft 22, the periphery of the disc 32 engages the edge of the cut out portion 39 of the disc 37 (Fig. 8). At the end of the counterclockwise movement of the shaft 22, the periphery of the disc 32 engages the edge of the cut out portion 40 of the disc 37 (Fig. 7). Thus the disc 37 is locked in position and the signal 13 cannot be moved manually from either of its intended positions.

The signal is safe because it automatically displays its danger-indicating face to traffic when a train is within the section of track to be guarded or the electrical current or mechanism fails for any reason. The signal can be moved to non-signalling position only by the operation of the motor, and the motor cannot function while the circuit is open (as it is when a train is within the section) or when the current or mechanism fails for any reason.

Rotating signals have usually been mounted above the control mechanism housing where ice and snow may interfere with or prevent intended movement of the signal. The novel mounting of our signal and provision of the shield 12 overcome this objection.

Obviously the signal shaft 38 may be extended upwardly through a suitable opening in the top of the housing so that signal 13 may be supported above the housing if desired, for example, where

the rotating signal is to be added to an existing flashing light signal.

The positive drive between the motor and weight and elimination of flexible connections such as used in prior art structures, is a decided advantage. Since our weight 46 is mounted to move in a vertical plane about a fixed horizontal axis, we obtain the greatest torque when the weight is in raised or horizontal position, and relatively great power is exerted on the signal shaft to turn the signal to danger position, with the expenditure of minimum power to raise the weight from vertical to horizontal position.

By mounting the lights directly on the control mechanism housing, all the wiring may be enclosed in said housing.

In this specification and in the claims, "danger position" means the face of the signal is at a right angle to the highway, and "clear" means the face of the signal is disposed longitudinally of the highway which is to be protected.

Changes may be made in details of construction without departing from the scope of our invention and we do not intend to be limited to the exact form shown and described, except as set forth in the appended claims.

We claim:—

1. A traffic signaling device comprising a signal movable to danger and clear positions, a frame, a horizontal shaft rotatably mounted in the frame, a weight fixed to the shaft and extending to one side of the shaft, a signal shaft mounted in the frame, a motor, operative connections including a vertical shaft between the motor and the weight carrying shaft for rotating the shaft and swinging the weight upwardly about the axis of the shaft, operative connections between the vertical shaft and signal shaft for turning the signal to clear position when the weight is being raised, means on the vertical shaft for preventing the weight carrying shaft from turning and means for automatically releasing the weight carrying shaft to allow the weight to swing downwardly by gravity and to actuate the operative connections between the vertical shaft and signal shaft to turn the signal to danger position.

2. A traffic signaling device comprising a signal movable to danger and clear positions, a frame, a horizontal shaft rotatably mounted in the frame, a weight fixed to the shaft and extending to one side of the shaft, a signal shaft mounted in the frame, a motor, operative connections including a vertical shaft between the motor and the weight carrying shaft for rotating the shaft and swinging the weight upwardly about the axis of the shaft, operative connections between the vertical shaft and signal shaft for turning the signal to clear position when the weight is being raised, means on the vertical shaft for preventing the weight carrying shaft from turning, and means for automatically releasing the weight carrying shaft to allow the weight to swing downwardly by gravity and to actuate the operative connections between the vertical shaft and signal shaft to turn the signal to danger position, said operative connections between the motor and weight carrying shaft comprising a motor driven horizontal shaft, a worm on the motor shaft, a worm wheel loosely mounted on the vertical shaft and

meshing with the worm, a bushing on the worm wheel, a spur gear on the bushing, a collar keyed to the vertical shaft, a pair of pinion gears located in and connected to the collar and meshing with the spur gear, a ring gear, loose on the vertical shaft, held against rotation and in mesh with the pinion gears, a bevel gear on said vertical shaft, and a bevel gear on said horizontal weight shaft, in mesh with said last mentioned bevel gear.

3. A traffic signaling device comprising a signal movable to danger and clear positions, a frame, a horizontal shaft rotatably mounted in the frame, a weight fixed to the shaft and extending to one side of the shaft, a signal shaft mounted in the frame, a motor, operative connections including a vertical shaft between the motor and the weight carrying shaft for rotating the shaft and swinging the weight upwardly about the axis of the shaft, operative connections between the vertical shaft and signal shaft for turning the signal to clear position when the weight is being raised, means on the vertical shaft for preventing the weight carrying shaft from turning, and means for automatically releasing the weight carrying shaft to allow the weight to swing downwardly by gravity and to actuate the operative connections between the vertical shaft and signal shaft to turn the signal to danger position, said means for preventing the weight carrying shaft from turning comprising a ratchet on the vertical shaft and a pivoted pawl engaging the ratchet, and said means for releasing the weight carrying shaft comprising an armature connected with the pawl, means for attracting the armature and means for releasing the armature and disengaging the pawl from the ratchet.

4. A traffic signaling device comprising a signal movable to danger and clear positions, a frame, a horizontal shaft rotatably mounted in the frame, a weight fixed to the shaft and extending to one side of the shaft, a signal shaft mounted in the frame, a motor, operative connections including a vertical shaft between the motor and the weight carrying shaft for rotating the shaft and swinging the weight upwardly about the axis of the shaft, operative connections between the vertical shaft and signal shaft for turning the signal to clear position when the weight is being raised, means on the vertical shaft for preventing the weight carrying shaft from turning, and means for automatically releasing the weight carrying shaft to allow the weight to swing downwardly by gravity and to actuate the operative connections between the vertical shaft and signal shaft to turn the signal to danger position, said operative connections between the vertical shaft and signal shaft comprising a disc mounted on the vertical shaft and having a pin carrying projection, a slotted, cut away disc fixed to the signal shaft, the pin being adapted to engage the slot, and the periphery of the disc on the vertical shaft being adapted to engage the cut away edges of the disc on the signal shaft when at the limits of its reciprocable movement and to lock the signal shaft against rotation until the vertical shaft is actuated.
